UNITED STATES PATENT OFFICE.

WILLIAM J. WETHERHEAD, OF TORONTO, CANADA.

COMBINATION FURNITURE.

No. 800,699.

Specification of Letters Patent.

Patented Oct. 3, 1905.

Application filed November 21, 1904. Serial No. 233,636.

To all whom it may concern:

Be it known that I, WILLIAM JOSEPH WETHERHEAD, mechanic, of the city of Toronto, in the county of York, in the Province 5 of Ontario, Canada, have invented certain new and useful Improvements in Combination Furniture, being an improvement on my Canadian Patent No. 87,099, issued the 10th day of May, 1904; and I do hereby declare o that the following is a full, clear, and exact description of the same.

The objects of my invention are to arrange in combination and in compact form a cupboard, cabinet, and refrigerator, and I construct the cupboard with a door that may be used to close the cupboard and be opened and arranged to form a table or work-board. I also arrange in extendible relation with the center and front part of the furniture a brace o that may be used for a shelf when closed in and a brace for the door or table part when the furniture is to be arranged to provide a table. The door to form the table part is preferably made of hinged sections, so that 5 when not being used as a table communication may be had with the cupboard part or with the two side parts of cupboard independent and without opening up the entire cupboard. I also prefer to arrange a tier of o drawers along each side of the cupboard. I attain these objects and show them as in the accompanying drawings, in which—

Figure 1 is a perspective view of my furniture, showing the table part closed. Fig. 2 is a perspective view of my furniture, showing the table part in position and the doors of the refrigerator and cabinet open.

Like letters refer to like parts throughout the specification and drawings.

o The furniture consists of three essential parts constructed in combination and arranged as an upright stand divided into two lower parts, the refrigerator *a* and cabinet *b* and the upper or cupboard part *c*. The refrigerator part *a* is divided into two parts, an ice-chest *d* and a cooling-box *e*, the ice-chest *d* being closed by a door *f* and the cooling-box by a door *g*. The details of construction of the refrigerator are similar to the ordinary refrigerators.

In the cooling-box *e* is arranged a perforated shelf *h*; but I do not want to confine myself to the one shelf, as I may provide one or more. Connected with the floor of the ice-chest and passing down through the cooling-box *e*, through the floor, and into a drip-tray

i is an overflow-pipe *j*. The drip-tray *i* is arranged underneath the refrigerator part *a* and is so constructed that it may be drawn from beneath the furniture for the purpose 60 of emptying.

Arranged along the front and bottom edge of the furniture is a hinged flap *k* for the purpose of hiding the tray *i* and to give a finished appearance to the furniture. 65

The cabinet part *b* is divided into two parts—a lower part *b'*, provided with a hinged door *b''*, and an upper part consisting of a drawer *l*.

The cupboard part *c* extends upwardly 70 and above the refrigerator part *a* and the cabinet part *b* and consists of the sides *m* and the top *n*. Extending the entire height of the cupboard at each side are a tier of drawers *p*. The remainder of the cupboard 75 *c* is divided into a tier of shelves *o*, extending between the tier of drawers *p*. Hinged to a shelf *s* intermediate the cupboard part *c*, the refrigerator *a*, and cabinet *b* is a door *g'*. The door *g'* consists of three sections *x y z* 80 hinged together, so that the three will open downward and form the table-top, and when so opened the three will be in one plane. The door *g'* is adapted to close over the shelves *o* and the drawers *p* and fasten into 85 place by engaging with the top *n* by a catch *r*, projecting from the edge of the section *y* of the door *g'*. The section *y* closes over the shelves *o*, and the sections *x* and *z*, respectively, close over the drawers *p*. The sections *x* and *z* being hinged to the center section *y* are adapted to be opened independently to communicate with either tier of drawers *p* when the door *g'* is closed and out of use as a table. 90

Adjacent and extending from the shelf part *s* is a brace *t*. The brace *t* consists of two side arms *u*, sliding in guideways *v* in the top and front face of the refrigerator *a* and cabinet *b*, the front ends of the arms *u* 100 being connected by a brace-arm *t'*.

When it is desirous to arrange the furniture as a table or work-board, the brace *t* is drawn outward and the door *g'* is let down and allowed to rest on the brace, which supports 105 the outer end and also prevents the door from sagging.

In Fig. 2 I show the door *g'* let down and supported on the brace *t* to provide a table or work-board.

By arranging the several parts in combination it will be seen I have provided for

several conveniences in a very compact form, where the combination will be adaptable to be used in small places and where room is an object.

5 What I claim as new, and desire to secure by Letters Patent, is—

1. In a combination furniture, an upright stand divided into three parts, and consisting of two lower, a refrigerator, and a cabinet 10 part, and an upper part consisting of a cupboard, having shelves and drawers, the said refrigerator and cabinet parts, having suitable doors, the cupboard part having a door adaptable to be let down, said door consisting of three hinged sections, a brace extendible from the front and middle part of said stand, said brace provided to support said door at right angles with said stand, said brace and door adapted to form a table or 15 work-board, substantially as specified.
2. In a combination furniture, an upright stand, said stand divided into a refrigerator part, a cabinet part, and a cupboard part, the said refrigerator part divided into an ice- 20 chest, and a cooling-box, said ice-box and 25

cooling-chest having suitable doors, an overflow pipe and a drip-tray arranged in combination with said refrigerator part, the said cabinet part consisting of a drawer, and a cabinet closed by a suitable door, a tier of 3 shelves arranged above said refrigerator and cabinet, and tier of drawers arranged at each side of said shelves, the said shelves and drawers constituting the cupboard part, said cupboard part adapted to be closed by a 3 door, said door hinged to the lower part of said cupboard, the said door consisting of three hinged sections and adapted to be let down and onto a brace, said brace arranged to be drawn outward from the middle 4 part of said stand, and support said door at right angles with said stand, substantially as specified.

Dated at Toronto this 13th day of July, 1904.

WM. J. WETHERHEAD.
